LIGHTNING ARRESTER

Elmer J. Wade, Pittsfield, Mass., assignor to
General Electric Company, a corporation of
New York

Application August 18, 1939, Serial No. 290,855

5 Claims. (Cl. 175—30)

My invention relates to lightning arresters and more particularly to arresters of the arc expulsion type. In this type of arrester a hollow insulating tube is provided with a conductive metal electrode at each end, one of the electrodes being grounded and the other electrode being spaced by a gap from an electrical conductor which is to be protected. One or both of the electrodes extend into the tube to provide an internal gap short enough to compel any discharge from the protected conductor to the grounded electrode to follow a path across the internal gap instead of a path between the electrodes along the outer surface of the tube. The insulating tube is composed of some suitable material such as hard fiber or is lined with some suitable material to give off quantities of gas under the influence of the heat of an arc and the evolution of this gas is so rapid that a high pressure is created inside the tube by the arc to blow it out through one of the electrodes which is provided with an opening for this purpose. The line electrode nearest the protected high voltage conductor tends to assume a voltage determined by the capacity between this electrode and the high voltage circuit and the capacity between this electrode and the grounded electrode and any other nearby grounded objects. The line electrode is usually much nearer the protected high voltage line than it is to the grounded electrode or any other grounded object so that it tends to assume a voltage very much above the grounded electrode. The distribution of this high voltage along the insulating tube is also not uniform. This non-uniform distribution of voltage tends to cause a discharge along the outer surface of the tube rather than across the internal gap even though the internal gap provides a shorter path for the discharge. The high voltage on the inner end of the line electrode also tends to produce corona at this point and this corona may in time attack the adjacent inner surface of the tube and result in a deterioration of the tube and a shortening of its useful life.

The general object of the invention is to provide an improved lightning arrester of the arc expulsion type including means for reducing the voltage of the line electrode to eliminate corona within the tube and to improve the distribution of the voltage along the outer surface of the tube to make it more certain that any discharge between the electrodes will follow a path across the internal gap instead of a path outside of the tube.

It is also an object of my invention to provide a new and improved lightning arrester which will be reliable in operation and which will have a relatively long life in service.

The invention will be better understood from the following description taken in connection

with the accompanying drawing in which Fig. 1 is a view of a short section of a three-phase high voltage electrical power circuit equipped with arc expulsion arresters constructed in accordance with the invention; Fig. 2 is a longitudinal sectional view of one of the arc expulsion arresters; and Figs. 3 and 4 are enlarged sectional detail views of the two ends of the arrester tube with their respective electrodes.

10 In the arrangement shown in Fig. 1, a supporting pole 10 with a cross-arm 11 supports the three conductors 12 of a three-phase high voltage electrical circuit. Brackets 13 secured to the pole 10 and cross-arm 11 and connected to a ground 14 support three arc expulsion arresters 15, one for each of the three high voltage conductors 12. Each arrester tube 15 includes an insulating tube 16 provided with a grounded electrode 17 secured to its supporting bracket 13 and a line electrode 18 spaced by a suitable gap from the corresponding high voltage conductor 12. The insulating tube includes two tightly telescoped tubes 19 of hard fiber or any suitable material which will give off a quantity of gas when heated by an arc. The line electrode 18 is in the form of a conductive cap of aluminum or other suitable metal and has a flange threaded onto the line end of the insulating tube. The line electrode 18 also includes a portion or metal pin 20 extending some distance into the opening 21 of the insulating tube and which may be spaced from the inside walls of the tube, as is illustrated in Figs. 2 and 3. The ground electrode 17 is also in the form of a cap with a flange threaded onto the adjacent end of the insulating tube, this ground electrode 17 having an opening 22 communicating with the opening 21 in the insulating tube. The ground electrode 17 may also include a metal tube 23 extending into an enlarged portion of the adjacent end of the opening 21 within the insulating tube. The opening 22 in the electrode 17 and the opening in the metal tube 23 should be as large in cross-section as the opening 21 in the insulating tube so that 25 the path of the gases expelled from the insulating tube may not be restricted.

30 In order to reduce the normal voltage between the electrodes 17 and 18 resulting from the proximity of the high voltage conductor 12, the outer surface of the insulating tube has a layer or coating 24 of high resistance material which is extended along the threaded outer surfaces at each end of the tube so as to make good contact with the two electrodes 17 and 18. Thus deterioration 35 of the inner tube walls adjacent the electrodes, and particularly adjacent the line electrode, due to corona formation at the electrodes, or within the tube, during normal voltage conditions is substantially precluded so that the reliability of 40 operation of the resulting device is improved and

its life made longer. It has been found possible to secure better and more uniform resistance characteristics if a sizing coating 25 is first applied to the insulating tube and then the resistance coating itself applied along the surface of the tube over this sizing coating. The sizing coating 25 may be a film of Bakelite varnish or it may be a few wraps of thin paper impregnated with Bakelite varnish. This sizing coating provides a suitable surface to which the resistance coating 24 will adhere satisfactorily and a surface to which a more uniform resistance coating may be applied than if it were applied directly to the outer insulating tube 19 which may be more or less porous. The sizing coating 25 further protects the resistance coating 24 from any moisture which may be present or which may reach the insulating tubes 19. After the resistance coating 24 has been applied, a protective coating 26 is applied over it to protect it from external moisture and from mechanical injury. This outside protective coating 26 may be a coating of Bakelite varnish or a few wraps of paper or cloth or both, impregnated with Bakelite varnish. The sizing coating 25 and the protective coating 26, 25 as well as the resistance coating 24, preferably extend slightly under the flanges of both electrodes 17 and 18 and the edges of these flanges are preferably spun down tightly onto the outer surface of the protective coating 26 to exclude moisture. Each of the coatings or layers 24, 25 and 26 may be cured by the application of heat to make their characteristics more permanent. Various materials may be used in the high resistance coating 24, excellent results having been obtained, however, with Bakelite varnish in which finely divided carbon black is distributed. In place of the carbon black, various other conductive and semi-conductive materials may be used, such as lamp black, graphite, tungsten sulfide, chromite, tin oxide, molybdenite, copper oxide, lead peroxide and silicon carbide. The resistance material forming the high resistance coating 24 may be applied to the surface of the sizing coating 25 by means of a spray gun. Very uniform results have been secured by rotating the tube in a lathe and applying the resistance coating from a spray gun mounted to slide at a fixed distance along a path parallel with the tube.

It has been found that elimination of corona at the inner end of the line electrode 18 and a good distribution of the voltage between the electrodes 17 and 18 along the surface of the tube are secured when the resistance of the resistance coating 24 is of the order of from 5 to 20 meg-ohms in a tube of such size that the length of the resistance coating was about 22 inches. This is a resistance of about one quarter to one megohm per inch of the resistance coating. With a tube 60 of this character, the normal voltage of the line electrode 18 was reduced from about 25,000 volts to approximately 1000 volts and the uniformity of distribution of the voltage along the surface of the tube was much improved. The comparatively low voltage of the line electrode 18 due to the resistance coating 24 eliminated all corona within the tube and the uniformity of the voltage distribution along the outer surface of the tube made the appearance of an external arc between the electrodes extremely unlikely.

The invention provides an improved lightning arrester of the arc expulsion type for discharging or interrupting high voltage, high frequency im- 75

pulses which is extremely reliable and which has a very long life in service.

The invention has been explained by describing and illustrating a particular construction of an arc expulsion tube and various modifications of details but it is obvious that other changes may be made without departing from the spirit of the invention and the scope of the appended claims.

What I claim as new and desire to secure by Letters Patent of the United States is:

1. A lightning arrester including an insulating tube of gas emitting material, an electrode at each end of the tube, at least one of the electrodes extending into the tube to provide an internal gap shorter than the external distance between the electrodes, and a high resistance coating along the outer surface of the tube and connecting said electrodes to increase the uniformity of distribution of the voltage between the electrodes whereby deterioration of the inner tube walls adjacent the electrodes due to corona formation at the electrodes during normal voltage conditions is substantially precluded.

2. A lightning arrester including an insulating tube of gas emitting material, an electrode at each end of the tube, at least one of the electrodes extending into the tube to provide an internal gap shorter than the external distance between the electrodes, a sizing coating on the outer surface of said tube, and a high resistance coating on said sizing coating and connecting said electrodes to increase the uniformity of distribution of the voltage between the electrodes.

3. A lightning arrester including an insulating tube of gas emitting material, an electrode at each end of the tube, at least one of the electrodes extending into the tube to provide an internal gap shorter than the external distance between the electrodes, a sizing coating including a varnish along the outer surface of said tube, and a high resistance coating on said sizing coating and connecting said electrodes to increase the uniformity of distribution of the voltage between the electrodes, said resistance coating including a varnish and a finely divided and at least semi-conductive material distributed in the varnish.

4. A lightning arrester including an insulating tube, at least one of the electrodes extending into the tube to provide an internal gap shorter than the external distance between said electrodes, means for preventing burning of the inner walls of said tube by corona forming on said one electrode during normal line voltage conditions comprising a high resistance coating along the outer surface of the tube and connecting said electrodes, a protective coating of insulating material provided over said high resistance coating so as substantially to preclude the alteration of the electrical characteristics of said coating during use of said arrester.

5. A lightning arrester including an insulating tube of gas evolving material, an electrode at each end of the tube, at least one of the electrodes extending into the tube to provide an internal gap shorter than the external distance between the electrodes, means for preventing burning of the inner walls of said tube by corona forming on said one electrode during normal line voltage conditions comprising a high resistance coating provided along the outer surface of said tube, a coating of weather-proof material provided over said high resistance coating so as substantially to preserve its electrical characteristics.

ELMER J. WADE.
